UNITED STATES PATENT OFFICE

FRANKLIN N. CONANT, OF NEWBURYPORT, MASSACHUSETTS, ASSIGNOR TO THE CHASE-SHAWMUT COMPANY, OF NEWBURYPORT, MASSACHUSETTS, A CORPORATION OF MASSACHUSETTS

ELECTRIC FUSE

Application filed September 27, 1930. Serial No. 484,851.

- This invention relates to electric fuses and especially those wherein the fusible element can be renewed.
- The fuse with which the present invention is more particularly concerned comprises a tubular insulating casing having external screw threads formed on the end thereof, with a thin metal shell or ferrule having complementary external and internal screw threads received on the screw threads of the casing and having screw threaded thereon an end cap or equivalent clamping or holding member for the fusible element which is located within the casing.
- One of the objects of the present invention is the provision of improved means which, in combination with the inter-engaged screw threads of the shell and casing, locks the shell to the casing against rotation on the screw threads of the casing.
- Another object of the invention is the provision of an external annular groove in the casing between the body and the screw threaded portion thereof into which a part of the metal shell is located so as to engage the walls of the groove and thereby hold the shell against axial displacement and thereby against rotation on the screw threads of the casing.
- A further object of the present invention is the provision of venting means for the interior of the casing which includes a venting channel that passes under the metal shell and is open to the atmosphere at or near the inner end of the shell, so that the metal vapors need not vent between the screw threads of the shell and end cap, as has been the case in some instances heretofore, with the result that the shell and end cap have become so strongly bonded together as to render removal of the end cap difficult.
- A yet further object is the provision of a fuse having a screw threaded casing provided with a generally axially-extended vent passage which cuts through the screw threads to a point slightly below the roots thereof, and a metal cap-holding ferrule screw threaded on the screw threaded portion of the casing over the vent passage and with a part of its internal screw threads forming a wall of the vent passage.
- Another object of the invention is the provision of a fuse having a vent passage that has a plurality of enlarged chambers with restricted channels connecting them in series so that the gas can expand in each of the chambers in succession and thereby be subjected to several stages of cooling and velocity and energy dissipation, whereby a larger and more effective vent passage can be used than has been usual heretofore.
- A further object is a fuse having a metal shell or ferrule screw threaded on the casing over a vent passage in the outer face thereof and wherein the roots of the internal screw threads are remote from, and the apexes are close to, the bottom of the vent passage so as to provide the aforesaid enlarged chambers and restricted interconnecting channels, the metal shell also constituting an effective cooling and heat-dissipating agent for the heated gases that are expelled from the casing through said passage.
- A further object is generally to improve the construction and operation of electric fuses.
- It has been found that when the shell and other thin-section parts that are subject to the arc vapors are made of a metal as brass, they can become burned by the hot vapors, but that when these parts are made of steel or some material having a melting temperature higher than the vaporizing temperature of the material of the fusible element, they are immune from burning; and this constitutes a further object of the invention.
- Fig. 1 is a side view of the electric fuse embodying the present invention.
- Fig. 2 is a sectional view taken along line 2-2 of Fig. 1.
- Fig. 3 is an end view of the casing of Fig. 2.
- Fig. 4 is an enlarged sectional detail of one end of the fuse casing.
- Fig. 5 is a section taken along line 5-5 of Fig. 4.
- Fig. 6 is a sectional detail taken along line 6-6 of Fig. 4.
- Fig. 7 is a sectional detail taken along line 7-7 of Fig. 5.
- The electric fuse herein shown as embody-

100

ing the present invention comprises a tubular enclosing casing 10 formed of insulating material, as fiber. The casing is provided with an end portion 12 which has a diameter that is somewhat less than the external diameter of the body portion of the casing, and has external screw threads 14 formed in said end portion. The end 16 of the casing is smooth on its outer periphery and extends beyond the end of the screw threads and has an exterior diameter slightly less than the diameter of the roots of the screw threads. An annular groove 18 having a rounded bottom is located between the body of the casing and the screw threaded portion thereof and has a diameter at the bottom approximately equal to the diameter of the smooth end portion 16 of the casing. A thin walled metal shell or ferrule 20 is received on the screw threaded portion of the casing. The shell is provided with internal screw threads 22 which engage the external screw threads of the casing and is also provided with external screw threads 24. The internal and external screw threads 22 are complementary and are formed by rolling the threads into the shell in a well known manner. The inner end of the shell is provided with an annular neck 26 which is rolled into the annular groove 18, and into intimate engagement with the walls of the groove, after the shell has been screw threaded on the casing so that the neck locks the shell permanently against axial displacement in either direction on the casing and thereby prevents the shell from being rotated to any deleterious extent on the screw threads. Spurs 28 also project inwardly from the shell into the material of the casing to hold the shell against rotation although the spurs are not essential. A metal tube 30 is fitted within the shell under the screw threaded portion thereof and is secured in place by rivets 32. Said tube is provided with an integral transverse end wall 34 which outstands beyond the body of the shell and overlies the end of the tubular casing. The end wall is provided with a semi-circular aperture 36 therein which has a flat fuse supporting ledge 38. A fusible element or link 40 is extended through the casing and has its outer end 42 extended through the opening 36 and reflexed over and in contact with the end wall 34. A metal end cap 44 is screw threaded upon the casing, and has internal screw threads 46 that engage the external screw threads 24 of the shell 20 and a transverse end wall 48 that forces the reflexed end 42 of the fuse against the wall 34 and thereby retains the fuse in position and also makes good electrical contact therewith. The end cap 44, between the internal screw threads and the end wall 48 thereof, is provided with an annular portion 50 which preferably is unthreaded and surrounds and is of sufficiently large diameter than the diameter of the end portion 16 of

the fuse casing to provide a venting passage therebetween. The end wall 48 of the end cap outstands from the end wall 34 of the fuse casing by the thickness of the end 42 of the fusible element and thus provides a venting space which is in communication with the interior of the casing through the opening 36.

In accordance with this invention improved means are provided to permit the escape of the high pressure gases and vapors formed within the interior of the casing when the fusible element blows and to cool the gases prior to their liberation into the atmosphere. To this end the fuse is provided with one or more, and as here shown four, venting channels 52 located at each end of the fuse. Said channels extend axially of the insulating casing, on the exterior thereof, from the reduced end portion 16 through the screw threaded portion 12 and transversely through the screw threads 14 thereof and through and across the annular groove 18 into the body portion of the casing where they have openings 54 at the surface of the body portion that are so arranged that the gases are discharged laterally away from the casing. The width of the slots can be anything desired, a width of approximately one-eighth of an inch giving good results. The bottom wall 56 of the groove is parallel with the axis of the casing and is slightly below the roots of the screw threads 12 and is substantially in line with the peripheral surface of the end portion 16 of the casing. The venting channels thus pass under the screw threaded metal shell 20 and the shell forms the top wall of the channels. The channels open into the annular passage between the end portion 16 of the casing and the end cap and thus are in communication, through the opening 36, with the interior of the casing and thus permit the gases and vapors in the interior of the casing to vent to the atmosphere and consequently to relieve the casing from high internal pressures.

Since the metal shell 20 constitutes the top of the channels the screw threads thereof traverse the channels, the apexes of the internal screw threads are closely spaced above the bottom walls of the channels and the roots of the threads are spaced a relatively great distance above the bottom walls. Thus the internal threads provide a plurality of expansion chambers 58 which are connected in series relation by the restricted passages 60. The gases are thus caused to pass from passage to passage in sequence and to expand and cool in each channel and to lose their velocity and energy by the formation of eddies in the enlarged chambers so that the gases are effectively cooled not only by the expansion chambers but by the cold metal ferrule that constitutes the top wall for said chambers and issue at low velocity from the

outlets of the channels. The arrangement of the series of expansion chambers and the small passages 60 that connect them constitute means which reduces the flow of the gases through the channels and thus permits the channels to be wide so that they will not be readily clogged by accumulation of metal dust.

In further accordance with this invention the thin threaded ferrule 20 in particular, and preferably also the tube 30 and other thin parts that are subject to the hot fuse vapors are composed of some material that has a melting temperature higher than the vaporizing temperature of the metal of the fusible element 40, since this vaporizing temperature is substantially the temperature of the arc vapors. Thus the metal parts will not become melted or burned when subjected to these vapors. When the fusible element is composed of zinc the shell and tube metal can be steel which has a higher melting temperature than the vaporizing point of zinc. The end cap 44 can be composed of a lower melting point metal since it is freely exposed to the cooling effect of the air and also since it has a relatively thick and heat-absorbent body.

A fuse having an externally screw threaded casing and an internally and externally thin metal cap holding shell is described and claimed in my co-pending application Serial No. 316,210, filed October 31, 1928.

I claim:

1. An electric fuse having an enclosing casing, an internally screw threaded metal shell on the end of the casing, a fuse engaging member carried by the metal shell, and a venting passage which communicates with the interior of said casing and passes between said casing and said shell and traverses the internal screw threads of said shell and has an outlet at the exterior of said casing.

2. An electric fuse having an externally screw-threaded enclosing casing, an internally screw-threaded metal shell on the end of the casing and the external screw threads thereof, a fuse engaging member engaged with said shell, and a venting passage in said casing which is in communication with the interior of said casing and which traverses said screw threads and passes between said shell and casing and has an outlet exteriorly of the casing beyond said shell.

3. An electric fuse having an enclosing casing, an internally screw-threaded metal shell on the end of said casing, a fuse engaging member engaged with said shell, and a venting passage which is in communication with the interior of said casing and which passes under said shell and between it and said casing and traverses said screw threads and has an opening exteriorly of the casing.

4. An electric fuse having an enclosing casing, an internally screw-threaded metal shell on the end of said casing, a fuse engaging member engaged with said shell, and a venting passage which is in communication with the interior of said casing and which passes under said shell and between it and said casing and transversely of said screw threads, said shell constituting an upper wall and said casing a lower wall of said passage, said passage having an outlet exteriorly of said casing, and the inner screw-threaded surface of said metal shell being exposed to the gas in said passage.

5. An electric fuse having an enclosing casing, a metal shell on the end of said casing, a fuse engaging member engaged with said shell, and a venting passage which is in communication with the interior of said casing and which passes under said shell and between it and said casing, said shell constituting an upper wall and said casing a lower wall of said passage, said passage having an outlet exteriorly of the casing, said metal shell being internally corrugated and the corrugations thereof traversing and being exposed to the gas in said passage.

6. An electric fuse having an enclosing casing, an internally screw threaded metal shell received on the end of said casing, a fuse engaging member engaged with said shell, and a venting passage located between said shell and said casing and being in communication with the interior of said casing and having an outlet exteriorly of said casing, said shell constituting an outer wall and said casing constituting an inner wall of said passage and the internal screw threads of said shell traversing said passage.

7. An electric fuse having an enclosing casing, an externally screw threaded cap holding shell located on the end of said casing, and a vent passage which extends longitudinally of the casing under said shell and has inlet and outlet openings on opposite sides thereof.

8. An electric fuse having an enclosing casing, an externally screw threaded cap holding shell located on the end of said casing, and a vent passage which extends longitudinally of the casing under said shell and has inlet and outlet openings on opposite sides thereof, said shell constituting the top wall and said casing constituting the bottom wall of said passage and said shell being exposed to the gas in said passage.

9. An electric fuse having an enclosing casing formed with a longitudinally extended venting passage at one end of its periphery, a metal shell carried by the end of the casing and overlying the major portion of said passage, and a fuse engaging member enclosing the end of said casing and said shell, said passage having an entrance into the interior of said member under said shell

and having an outlet between the other end of said shell and said casing.

10. An electric fuse having a tubular casing, an exteriorly screw threaded metal shell surrounding the end of and carried by said casing, an end cap screw threaded onto said shell, and a venting passage extended longitudinally of said casing under said shell and having communication with the interior of said end cap and having an outlet exteriorly of said casing.

11. An electric fuse having an enclosing casing provided with a venting slot in the peripheral end portion of said casing that is extended longitudinally of the casing, an exteriorly screw threaded metal ferrule that is carried by the end of said casing and overlies said slot, and an end cap that is screw threaded on said shell, said slot having an entrance that communicates with the interior of said end cap and having an outlet that is open exteriorly of said casing.

12. An electric fuse having an enclosing casing, external screw threads on the end of said casing, a venting slot which is extended longitudinally of said casing through said screw threads and below the roots of said threads, a metal shell having external screw threads and internal screw threads which are received on the screw threads of said casing, said shell constituting the top wall of said slot, and an end cap screw threaded on the external screw threads of said shell, said slot having an entrance in the interior of said end cap and having an outlet exteriorly of said casing.

13. An electric fuse having an insulating enclosing casing, external screw threads on the end of said casing, a slot which extends longitudinally of said casing across said screw threads and has a bottom wall which is located below the roots of said threads, an internally and externally screw threaded metal ferrule having its internal screw threads engaged with the external screw threads of said casing, said metal shell constituting the top wall of said slot and having its internal screw threads traversing said slot with the apexes thereof terminated close to the bottom wall of said slot, and an end cap screw threaded on said shell, said slot having an entrance in the interior of said end cap and having an outlet exteriorly of said casing beyond said shell.

14. An electric fuse having an enclosing casing provided with external screw threads on the end thereof, a slot which extends longitudinally through said screw threads and has a bottom wall which is located below the roots of said threads, a metal shell having external screw threads and internal screw threads that are engaged with the screw threads of said casing, said metal shell constituting an outer wall of said slot and having its internal screw threads exposed to

the gas in said slot, and the apexes of said threads terminated in confronting and spaced relation with the bottom wall of said slot, the spaces between said internal screw threads constituting a series of communicating expansion chambers for the gas passing through said slot, and an end cap screw threaded on the external screw threads of said shell, said slot having an entrance that communicates with the interior of said cap and an outlet exteriorly of said casing.

15. In an electric fuse, a tubular enclosing casing of insulating material having an externally screw-threaded end portion and an annular peripheral groove between the body of the casing and said screw threaded portion, and a metal cap-holding shell having external screw threads and internal screw threads that are engaged with the screw threads of said casing and having an annular unthreaded end portion that is located in said groove and engages opposite walls thereof and constitutes means which cooperates with said screw threads in retaining said shell against rotation on said casing.

16. In an electric fuse, a tubular insulating enclosing casing having an externally screw threaded end portion and an endless annular groove which is sunk into the casing adjacent the screw threads, a metal cap-holding shell having external cap-receiving screw threads and internal screw threads which engage the external screw threads of said casing, and also having a part which is sunk into said groove and closely engages the opposite walls thereof and cooperates with said engaged screw threads in holding said shell against rotation.

17. In an electric fuse, a tubular enclosing casing of insulating material having external screw threads on the end of the casing, a peripheral annular groove located at the end of said screw threads and between said screw threads and the body of the casing, and a metal shell having external screw threads and internal screw threads that are engaged with the screw threads of said casing, an unthreaded annular end portion which is received in said groove and which cooperates with said screw threads in holding said shell against rotation on said casing.

18. In an electric fuse, an enclosing casing of insulating material having external screw threads on the end of the casing, and a peripheral annular groove located between said screw threads and the body of the casing, a thin metal shell having complementary external and internal screw threads received in the screw threads of said casing and having an unthreaded end portion which is sunk into and closely engages with the wall of said groove and cooperates with said screw heads to hold said shell against rotation.

19. In an electric fuse, an enclosing casing of insulating material having external screw

threads on the end of the casing, and a peripheral annular groove located between said screw threads and the body of the casing, a thin metal shell having complementary external and internal screw threads received in the screw threads of said casing and having an unthreaded end portion which is sunk into and closely engages with the wall of said groove and cooperates with said screw 10 threads to hold said shell against rotation, said shell also having spurs which are sunk into said casing.

20. In an electric fuse, an enclosing casing, and venting means therefor comprising a metal member which surrounds said casing and has a corrugated inner surface that confronts and is closely spaced from the outer periphery of said casing, the spaces between two corrugations constituting expansion chambers, 20 and means to conduct gases from the interior of said casing in series through said expansion

chambers and thence to the atmosphere.

21. An electric fuse having an enclosing casing, a metal shell on the end of said casing, a fusible element within said casing, a fuse-engaging member engaged with said shell, and a venting passage which is in communication with the interior of said casing and which passes under said shell and between it and said casing and has an outlet exteriorly of said casing, said shell constituting an upper wall of said passage and the inner surfaces of said shell being exposed to the vapors of said fusible element in said passage when said fusible element melts, said shell being composed of a metal having a melting temperature that is higher than the vaporizing temperature of said fusible element so that it cannot be melted by the hot vapors of the fusible element at the time the fuse operates.
